UNITED STATES PATENT OFFICE.

WILLIAM BARKER, JR., OF TROY, NEW YORK, ASSIGNOR TO LION COLLARS & SHIRTS, INC., OF TROY, NEW YORK, A CORPORATION OF NEW YORK.

SOFT-FOLD COLLAR.

Application filed July 20, 1921. Serial No. 486,018.

To all whom it may concern:

Be it known that I, WILLIAM BARKER, Jr., a citizen of the United States, residing at Troy, in the county of Rensselaer and State of New York, have invented new and useful Improvements in Soft-Fold Collars, of which the following is a specification.

Reference may be had to the accompanying drawings, and the reference characters 10 marked thereon, which form a part of this specification. Similar characters refer to similar parts in the several figures therein.

This invention is applicable to collars of various kinds and is more particularly applicable to soft fold-collars.

The principal object of the invention is to make a collar or collar member in a manner to conveniently and economically form the complete collar or one of its members of an 20 integral piece of woven fabric.

Other objects of the invention will appear in connection with the following description.

Fig. 1 of the drawings is a plan view of a 25 blank cut from an integral piece of fabric adapted for use in the manufacture of a soft fold-collar in accordance with my invention.

Fig. 2 is a similar view showing the cut 30 edge of the top of the collar provided with a stitched binding by overseaming said edge.

Fig. 3 is a vertical cross-section of the same taken on the broken line 3-3 in Fig. 2.

Fig. 4 is a view similar to Figs. 1 and 2 35 showing the edges of the blank, including said bound edge of the top, inturned.

Fig. 5 is a similar view showing the inturned edges of the top of the collar stitched to the body-portion of the top independently 40 of the binding stitching, and showing the band-portion of the collar completed by stitching to the band-portion of the folded blank shown in Fig. 4, a band-facing with inturned edges.

Fig. 6 is a cross-section of an end tab- 45 portion of the completed collar taken on the broken line 6-6 in Fig. 5.

Fig. 7 is a similar view taken on the 50 broken line 7-7 in Fig. 5 through the band and top of the collar.

Fig. 8 is a view similar to Fig. 2, broken-away, illustrating another method of applying a stitched binding to the cut-edge of the top of the collar.

Fig. 9 is a vertical cross-section of the

same taken on the broken line 9-9 in Fig. 8.

Fig. 10 is a view similar to Fig. 5, showing the band-portion of the collar faced only at its buttonholed ends, the intermediate portion of the cut-edge of the band being 60 provided with a stitched binding and inturned.

I have shown in Fig. 1 a blank cut from an integral web of fabric of the general shape of a soft fold-collar laid out flat, and of an 65 area greater than that of the finished collar by the area of material to be inturned along the edges of the blank in the operation of making the collar.

For certain purposes of the invention said 70 blank may be made of any desired fabric, but I prefer to employ a fabric woven either as a single ply fabric or as a multiple ply fabric in an integral piece.

Preliminary to folding this blank to the 75 proper size and form for the finished collar, I apply to certain cut-edges of the blank a stitched binding whereby the cut threads of the fabric are prevented from fraying or raveling.

In Fig. 2 I have shown such a stitched binding applied to the cut-edges of the top-portion, 1, of the blank, the stitched binding being in the form of an overseam or cat-stitching, 2.

I then place the blank in an ordinary folding machine and inturn all the edges of the blank including the edges of the top bound by the stitched binding, 2, to the form shown in Fig. 4, which form is that of the finished 80 collar.

The inturned edges of the top-portion, 1, shown at 3 in Fig. 4, are then secured by one or more lines of stitching, 4, to the body of the top-portion, 1, independently of the 85 binding stitching by which the cut-edge of the top is prevented from fraying or raveling.

In completing the manufacture of the collar from the folded blank shown in Fig. 4, wherein the cut-edges of the band-portion, 5, of the blank are simply inturned as shown at 6, and not provided with a stitched binding, I superimpose upon the band-portion of the blank a band-facing ply, 7, of 100 fabric, inturned along its edges and secure the same by stitching, 8, in the usual manner of stitching together the plies of a collar band.

The band is then provided with button- 110

holes, 9, in the usual manner to complete the collar.

As thus made the top-portion, 1, of the collar may be folded over upon the band 5 in the usual manner to make a fold collar; and when so folded and worn, all parts of the collar exposed to view present a finished appearance with no indication that the top-portion, 1, is made of a single integral piece 10 of material.

In Figs. 8 and 9, I have shown the cut-edge of the top-portion of the blank provided with a stitched binding in the form 15 of a tape, 10, folded over the cut-edge and secured by stitching, 11.

After the edge of the top-portion of the blank as shown in Fig. 1, has been provided with the stitched binding tape, 10, as shown in Figs. 8 and 9, the manufacture of the 20 collar is completed in the same manner as with the blank shown in Fig. 2.

In carrying out my invention the manner of finishing the cut-edge of the blank by providing the same with a stitched binding 25 and then inturning the edge may be employed with respect to the cut-edges of the top member, 1, or the band member, 5, or both.

In Fig. 10 I have shown the blank finished 30 in the manner above described by providing the same with a stitched binding and inturning the bound edge except at the buttonholed ends of the band-portion whereat I have applied facings, 12, stitched to 35 the body-portion of the band to cover and conceal the inturned edges of the tab ends of the band which are more less exposed to view in use, thus giving to said ends the appearance of an ordinary soft fold-collar.

40 In this construction the bottom edge of the band is finished by a stitched binding and inturning the bound edge, as above de-

scribed with respect to the cut-edges of the top-portion, 1.

In employing a binding in the form of the 45 tape, 10, I prefer to cut the binding on the bias from woven fabric.

What I claim as new and desire to secure by Letters Patent is—

1. A collar including a band member and 50 a top member, said band member having inturned edges at the ends thereof, and facings with inturned edges stitched to the band members at the ends thereof, the in-turned edges of said band member being 55 concealed by said facings.

2. A collar including a band member and a top member formed of a single piece of 60 fabric, said band member having inturned edges at the ends thereof and facings with in-turned edges stitched to the band member at the ends thereof, the in-turned edges of said band member being concealed by said facings.

3. A collar including a band member and 65 a top member formed integral with each other, and having inturned edges on all sides stitched to the body of the collar, said in-turned edges being exposed except at the ends of the band member whereat they are 70 concealed by facings with in-turned edges stitched to the body of the band member.

4. A collar including a band member and a top member, and having inturned edges 75 on all sides stitched to the body of the collar, facings with in-turned edges stitched to the body of the band member at the ends thereof, said first in-turned edges being exposed except at the ends of the band member whereat they are concealed by said fac- 80 ings.

In testimony whereof, I have hereunto set my hand this 16th day of July, 1921.

WILLIAM BARKER, JR.
